VALVE MECHANISM FOR ROCK DRILLS

Charles A. Hultquist, Los Angeles, Calif., assignor
to Independent Pneumatic Tool Co., Chicago,
Ill., a corporation of Delaware

Application November 28, 1934, Serial No. 755,155

10 Claims. (Cl. 121—19)

My invention relates to valve mechanism for rock drills, and the objects of my invention are:

First, to provide a valve mechanism for rock drills which provides a correct distribution of the compressed fluid used in operating the tool in order to obtain greater drilling speed with reduced power consumption;

Second, to provide a valve mechanism of this class for rock drills so constructed that more compressed fluid will be admitted by the valve in its operation to either end of the cylinder bore at the start of each stroke of the drill hammer than later in the strokes; and

Third, to provide a new and novel distributing valve and valve chest which is very simple and economical of construction, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a back end view of the rock drill with a portion of the throttle broken away and in section to facilitate the illustration; Fig. 2 is a longitudinal sectional view of the drill on the line 2—2 of Fig. 1 and showing the air distributing valve in its rearward position for admitting fluid to the rear end of the cylinder bore in position for driving the hammer piston on its forward or working stroke; Fig. 3 is a sectional view of the head 5 through 3—3 of Fig. 1, and Fig. 4 is a fragmentary sectional view on an enlarged scale through 4—4 of Fig. 2 and showing the distributing valve in its forward position for admitting fluid to the forward end of the cylinder bore for driving the hammer piston on its rear or return stroke.

Similar characters of reference refer to similar parts and portions throughout the several views of the drawings.

As in the conventional rock drill of this class, my rock drill is provided with a back head 5 at the back end of the rock drill which back head is provided with a throttle housing 6 in which operates a throttle valve 7 which is turned to different positions by a throttle handle 8 and is held in varied positions by a ratchet pawl and spring, as shown best in Figs. 1 and 3 of the drawings, which are conventional and may be omitted,

if desired, without affecting the operation of my valve mechanism. Screwed into the housing 6 at the opposite end from the throttle handle 8 is an air inlet spud 9 which is the main air inlet to the rock drill. The head 5 is also provided with a hole 10 which is adapted to receive the handle in the conventional manner for supporting the drill during the drilling operations.

Seated partly in the back head 5 and partly in the counter bore 11 of the rear cylinder 12 is a conventional ratchet mechanism 13 which consists of the conventional ratchet ring, pawls, springs and the head of the rifle bar 14, not shown in detail except the end of the rifle bar 14. This rifle bar 14 is provided with helical flutes which are adapted to engage helical ridges cut in the rifle nut 15 which is screwed into the hammer piston 16, thus providing means for rotating the hammer piston 16 when it travels back and forth in the cylinder 12. It will be noted that this rotating movement is conveyed to the chuck driver 17 by reason of flutes cut on the hammer extension 18 which engage notches 19 in the chuck driver 17. This in turn rotates the drill steel 20 which is supported in the chuck driver 17 by means of a hexagon shank 21. The back head 5 and front head 22 and the intermediate parts are held in rigid alignment and position by two side bolts 23, shown in Fig. 1 of the drawings, which pass through lugs in the back head 5 and front head 22.

It will be here noted that the structure so far described in detail is substantially conventional in form of pneumatic rock drills of this class but is necessary for combinative relation with the valve mechanism described hereinafter.

Mounted in the counter bore 11 of the rear cylinder 12 is a valve chest 25 and reciprocally mounted in this valve chest 25 is a tubular sliding distributing valve 24 which slides on the bearing 26 which bearing 26 is made integral with the flange 27 which is clamped in central alignment between the rearward end of the valve chest 25 and the ratchet mechanism 13 in the bore 11. The valve bearing 26 and flange 27 are hollow and the rifle bar 14 extends through the valve bearing 26 and flange 27. The valve chest 25 is provided with a central fluid supply groove 28 and with fluid reservoir chambers 29 and 30 on opposite sides thereof. The diameters of the bores in the ridges 31 and 32 are of equal dimensions, while the bore in the ridge 33 is larger in diameter than the bores in the ridges 31 and 32, and the bore in the ridge 34 is larger than the bore in the ridge 33. A counter bore 35 in the

rear end of the valve chest 25 communicates with the front end 36 of the cylinder bore through inlet port 37. The central supply groove communicates with a throttle valve 7 and supply chamber 38 through ports 39, shown best in Fig. 2 of the drawings.

The distributing valve 24 has four flanges from its rear end forwardly, designated 40, 41, 42 and 43, shown best in Fig. 4 of the drawings. The flanges 41 and 42 are of equal dimensions but smaller in diameter than the bores of the ridges 33 and 34 in which they operate, thus leaving spaces 44 and 45 between the flanges 41 and 42 and ridges 33 and 34 which are constantly open for the flow of fluid into the chambers 29 and 30. The spaces 44 and 45 control the amount of fluid required for driving the hammer piston 16 on its forward and rearward strokes. The two flanges 40 and 43 are of equal dimensions but thicker and of heavier construction than the flanges 41 and 42 because they serve in conjunction with the ridges 31 and 32 as stops for limiting the travel of the distributing valve 24. The flanges 40 and 43 are spaced on the valve in relation to the inner face of the ridges 31 and 32 to provide the valve with a very short travel and against which they seat intermittently and make an airtight joint. These flanges 40 and 43 are smaller in diameter than the flanges 41 and 42, therefore the flanges 41 and 42 have a larger pressure area on their outer faces 46 and 47 than the flanges 40 and 43 have on their inner faces 48 and 49. The difference in the diameters of the constrictions in the valve chest on opposite sides of the central inlet in the valve chest which results in a different space at the opposite sides of the inlet in cooperation with the resultant varying static pressure provides means for facilitating the starting operation of the tool and also accelerates the movement of the valve while in operation.

It will be here noted that no confusion can occur in assembling this valve mechanism because the flanges 41 and 42 are spaced equally from the center of the valve 24 and are of the same dimensions as the flanges 40 and 43, although smaller in diameter than the flanges 41 and 42, are of equal dimensions and spaced equally from the middle of the valve. Therefore, it will be seen that the valve 24 will operate equally as well if turned end for end, or reversed in position.

The operation of my valve mechanism is as follows: Referring generally to Fig. 2 of the drawings, fluid under pressure enters the back head 5 through the inlet spud 9, shown in Figs. 1 and 4 of the drawings, into the hollow portion 50 of the throttle valve 7. Thence through inlet port 51 in the throttle valve 7 and the port 52 in the back head 5 and into the chamber 38. Thence through the supply ports 39 into the central supply groove 28 of the valve chest 25. From there it is distributed by the distributing valve 24. It will be noted that the valve 24 is shown in its rearward position in Fig. 2 of the drawings and the fluid flows through the spaces 44 and 45 into the reserve chambers 29 and 30, the flange 40 being seated against the inner side of the ridge 31. From the chamber 30 the fluid flows through the opening 53 into the rear end 54 of the cylinder bore where it operates the hammer piston 16 driving it forward on its working stroke. The fluid pressure against the outer side of the flange 43 and the end face 55 of the valve 24 holds the valve in its rearward position,

as shown in Fig. 2 of the drawings. In its forward travel the hammer piston 16 has passed over and closed the exhaust port 56, shown in Fig. 2 of the drawings, and is now compressing fluid in the front end 36 of the cylinder bore. This compressed fluid flows through the port 37 into the counter bore 35 of the valve chest 25 where it acts on the rear end 57 and pressure area 58 of the valve 24. As the hammer piston 16 continues on its forward or working stroke the exhaust port 56 is uncovered at the rear of the hammer piston 16 and exhaust is now taking place in the rear end 54 of the cylinder bore.

As the pressure against the end face 55 and outer side of the flange 43 of the valve 24 is lessened, the pressure created against the rear end 57 and pressure area 58 moves the valve to its forward position, as shown in Fig. 4 of the drawings.

The shifting of the valve is arranged by applicant's construction and mode of operation to occur a moment before the hammer extension 18 strikes the end of the drill shank 21. The fluid is now flowing through passages 44 and 59 into the counter bore 35, thence through the cylinder port 37 into the forward end 36 of the cylinder bore for driving the hammer piston 16 rearwardly. On its return stroke the hammer piston 16 passes over and closes the exhaust port 56 which causes compression in the rear end 54 of the cylinder bore. As the hammer piston 16 continues on its rearward stroke it passes completely over the exhaust port 56. Exhaust is now taking place in the front end 36 of the cylinder bore. As the pressure diminishes against the end face 57 and outer side of the flange 40 of the distributing valve 24, the pressure caused in the rear cylinder bore 54 acting on the end face 55 and the pressure area 60 moves the valve to its rearward position and the hammer piston 16 will again start on its forward stroke.

The above-described operation of the different parts will continue as long as fluid under pressure flows into the groove 28 of the chest 25.

Because of the fluid reserve in the chambers 29 and 30, the fluid supplied to drive the hammer piston 16 forwardly and rearwardly is greater at the initial start of the stroke than at any other time. This provides a quick start for the hammer piston 16 from each end of the cylinder bore which increases the speed of the hammer piston and more work is accomplished than would be possible by a valve mechanism where there are no reserve chambers.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a valve mechanism for rock drills, a cylindrical bearing, a hollow tubular valve member slidably thereon provided with two relatively large diameter flanges in spaced relation at the middle thereof and with two smaller diameter flanges one near each end of said valve member in spaced relation to the first mentioned flanges, a valve chest surrounding said valve member, and constrictions overhanging the end flanges of said valve member and adapted to be engaged

- by said flanges with the backward and forward movement of said valve member, and a pair of constrictions in said valve chest intermediate the end constrictions in spaced relation to each other 5
5. in operative relation with the middle flanges of said valve member, one of said constrictions having a larger diameter bore than the other, and a fluid conducting channel between said intermediate constrictions in said valve chest.
10. 2. In a valve mechanism for rock drills, a cylindrical bearing, a hollow tubular valve member slideable thereon provided with two relatively large diameter flanges in spaced relation at the middle thereof and with two smaller diameter flanges one near each end of said valve member in spaced relation to the first mentioned flanges, a valve chest surrounding said valve member, and constrictions overhanging the end flanges of said valve member and adapted to be engaged by said flanges with the backward and forward movement of said valve member, a pair of constrictions in said valve chest intermediate the end constrictions in spaced relation to each other in operative relation with the middle flanges of 20
25. said valve member, one of said constrictions having a larger diameter bore than the other, a fluid conducting channel between said intermediate constrictions in said valve chest, and a counter bore at the rearward end of said valve chest in communication therewith.
30. 3. In a valve mechanism for rock drills, a cylindrical bearing, a hollow tubular valve member slideable thereon provided with two relatively large diameter flanges in spaced relation at the middle thereof and with two smaller diameter flanges one near each end of said valve member in spaced relation to the first mentioned flanges, a valve chest surrounding said valve member, and constrictions overhanging the end flanges of 35
40. said valve member and adapted to be engaged by said flanges with the backward and forward movement of said valve member, and a pair of constrictions in said valve chest intermediate the end constrictions in spaced relation to each other in operative relation with the middle flanges of 45
45. said valve member, one of said constrictions having a larger diameter bore than the other, and a fluid conducting channel between said intermediate constrictions in said valve chest, said chest provided with two fluid chambers formed between the intermediate constrictions and the outer constrictions of said valve chest.
50. 4. In a valve mechanism for rock drills, a cylindrical bearing, a hollow tubular valve member slideable thereon provided with two relatively large diameter flanges in spaced relation at the middle thereof and with two smaller diameter flanges one near each end of said valve member in spaced relation to the first mentioned flanges, 55
60. a valve chest surrounding said valve member, and constrictions overhanging the end flanges of said valve member and adapted to be engaged by said flanges with the backward and forward movement of said valve member, a pair of constrictions in said valve chest intermediate the end constrictions in spaced relation to each other in operative relation with the middle flanges of 65
70. said valve member, one of said constrictions having a larger diameter bore than the other, a fluid conducting channel between said intermediate constrictions in said valve chest, and a counter bore at the rearward end of said valve chest formed by one of said constrictions, said chest provided with two fluid chambers formed be- 75
- tween the intermediate constrictions and the outer constrictions of said valve chest.
5. In a valve mechanism for rock drills, the combination with a tubular flanged sliding valve of an annular tubular valve chest provided with two spaced constrictions extending inwardly intermediate the ends of said valve chest and leaving a fluid intake channel between said constrictions, the bores of said constrictions being of unequal diameter, and also provided with two inwardly extending outer constrictions spaced from said middle constrictions and leaving annular fluid reservoir chambers therebetween. 10
6. In a valve mechanism for rock drills, the combination with a tubular flanged sliding distributing valve of an annular tubular valve chest provided with two spaced constrictions extending inwardly intermediate the ends of said valve chest and leaving a fluid intake channel between said constrictions, the bores of said constrictions being of unequal diameter, and also provided with two inwardly extending outer constrictions spaced from said middle constrictions and leaving annular fluid reservoir chambers therebetween, the bores of said outer constrictions being of equal diameter. 15
7. In a valve mechanism for rock drills, the combination with a tubular flanged sliding distributing valve of an annular tubular valve chest provided with two spaced constrictions extending inwardly intermediate the ends of said valve chest and leaving a fluid intake channel between said constrictions, the bores of said constrictions being of unequal diameter, and also provided with two inwardly extending outer constrictions spaced from said middle constrictions and leaving annular fluid reservoir chambers therebetween, the bores of said outer constrictions being of equal diameter, said valve chest also provided with a counter bore between the rear outer constrictions 20
30. and the end of said valve chest. 35
8. In a valve mechanism for rock drills, an annular tubular valve chest provided with two spaced constrictions extending inwardly intermediate the ends of said valve chest and leaving a fluid intake channel between said constrictions, the bores of said constrictions being of unequal diameter, also provided with two inwardly extending outer constrictions spaced from said middle constrictions and leaving annular fluid 40
50. reservoir chambers therebetween, the bores of said outer constrictions being of equal diameter, and a tubular valve slidably mounted in said valve chest provided with outer flanges near the opposite ends of said valve of a diameter adapted 55
60. to engage the inner side walls of said outer constrictions of said valve chest and arranged to provide clearance for slight shiftable movement between said flanges and said outer constrictions. 65
9. In a valve mechanism for rock drills, an annular tubular valve chest provided with two spaced constrictions extending inwardly intermediate the ends of said valve chest and leaving a fluid intake channel between said constrictions, the bores of said constrictions being of unequal diameter, also provided with two inwardly extending outer constrictions spaced from said middle constrictions and leaving annular fluid reservoir 70
75. chambers therebetween, the bores of said outer constrictions being of equal diameter, and a tubular valve slidably mounted in said valve chest provided with outer flanges near the opposite ends of said valve of a diameter adapted to engage the inner side walls of said outer constrictions of said valve chest and arranged to provide clearance 75

for slight shiftable movement between said flanges and said outer constrictions, said valve also provided with a pair of spaced flanges on the middle portion of said valve positioned to operate in the bores of said middle constrictions of said valve chest, said flanges being of equal diameter whereby the spaces between said flanges and middle constrictions are varied.

- 5 10. In a valve mechanism for rock drills, an annular tubular valve chest provided with two spaced constrictions extending inwardly intermediate the ends of said valve chest and leaving a fluid intake channel between said constrictions, the bores of said constrictions being of unequal diameter, 15 also provided with two inwardly extending outer constrictions spaced from said middle constrictions and leaving annular fluid reservoir chambers therebetween, the bores of said outer constrictions being of equal diameter, a tubular valve

slidably mounted in said valve chest provided with outer flanges near the opposite ends of said valve of a diameter adapted to engage the inner side walls of said outer constrictions of said valve chest and arranged to provide clearance for slight shiftable movement between said flanges and said outer constrictions, said valve also provided with a pair of spaced flanges on the middle portion of said valve positioned to operate in the bores of said middle constrictions of said valve chest, 10 said flanges being of equal diameter whereby the spaces between said flanges and middle constrictions are varied, and said valve provided with extended annular end portions spaced from the inner side of the bore of said outer constrictions 15 to provide pressure spaces for the sides of the flanges of said valve.

CHARLES A. HULTQUIST.
